JOHN FUSCO, OF NEW HAVEN, CONNECTICUT

CUTLERY POLISHING MACHINE

Application filed August 8, 1929. Serial No. 384,391.

This invention relates to cutlery finishing machines. Cutlery blades to-day are largely blanked from sheets of stainless steel and require no grinding like, for instance, a forged blade. The steel rolling process will leave well defined marks which will appear in the blades blanked out of the rolled sheets.

The blades are first passed between opposed wheels carrying abradent material coarse enough to taper the blade and form the cutting edge and also remove as much as possible the marks left by the rolling process. These coarse abrasion wheels, however, leave marks of their own which the succeeding finer abrasion wheels are bound to follow, but cannot entirely remove, so but what they can readily be seen after hand buffing, which is too expensive an operation to be continued long enough to entirely remove the preceding imperfections.

The object of the present invention is to employ polishing rolls in place of the narrow wheels and to mechanically pass the blades through the rolls in two directions, and thus break up not only the lines of the rolling process, but also effectually destroy the lines formed by the initial coarse abrasion wheels, so that but little hand buffing is required to produce a mirror-like finish.

In describing the invention in detail reference will be had to the accompanying drawings wherein like characters of reference denote corresponding parts in the several views in which

Figure 1 represents a front elevation of the machine in operation—

Figure 2 is a plan view of the machine in operation showing a knife blade passing through the rolls—

Figure 3 is a partly broken end elevation of the machine looking in the direction of arrow *a* of Figure 2 with the traveling carriage and its mechanism and support removed, and

Figure 4 is a cross sectional view of car-

riage supporting frame on line *b*—*b* of Figure 2.

The bed 1 supports the principal members of the machine comprising, in part, the standards 2, 3, and 4, in which are located the floating boxes 5, 6, and 7. The shaft 8 of the upper polishing roll 9 has one end journaled in the box 7, while its other end is detachably connected to the sleeve 10 by the pin 11, and the sleeve to the short shaft 12 journaled in the boxes 5 and 6 and carrying the pulley 13 by means of which the upper polishing roll is rotated through the medium of the belt 14 and pulley 15 on the main driving shaft 16 journaled in the standards 17, 18, and 19 is the main shaft driving pulley. 20 is the lower polishing roll on the shaft 21 journaled in the boxes 22, 23, 24, mounted in the several standards, and 25 is the driving pulley for this lower roll shaft.

26 is a bar supported on the springs 27, 28 and 29, and 30, 31 and 32 are studs passing freely through the bar 26 and each is anchored respectively in the upper floating boxes 5, 6, and 7, as shown in Figure 3. The several springs also pass freely through the caps 2^a, 3^a, and 4^a, and rest on adjusting nuts, one, 33, being shown in Figure 3. 34 is a bar pivotally supported in the ears 35 attached to the bar 26, and 36 is a rod pivotally connected to this bar and also to the treadle lever 37.

38 is a plate mounted on the bed for supporting the mechanism pertaining to the traveling knife holding carriage comprising an angular support having the base 39 and the upright 40, Figure 4. 41 is a continuously driven feed screw, Figure 1, journaled in the standards 42, 43, Figure 1, rising from the base 39. The outer end of this screw is connected to the short rotatable shaft 44 by the universal coupling 45, and 46 is the driving pulley for the short shaft 44 and feed screw. The feed screw and support are preferably located at an acute angle to the bed 1 for a

special purpose to be more fully explained.

47 is a rod mounted in the ears 48, 49, supported on the upright 40. The knife holding carriage comprises the arms 50 freely mounted on the rod 47 and are attached to the plate 51, and 52 is a block located between said arms and is slidably mounted on the rod 47 and against the upright 40 to prevent its turning on said rod while permitting said arms 50 to do so.

53 is a plate secured to and depending from the plate 51, and it carries the half nut 54, Figure 4, to engage with the feed screw 41. 55 is a screw threaded in plate 53, and freely entering a hole in the block 52 and it carries the spring 56 located between the plate 53 and block 52 to swing the carriage and disengage the nut 54 from the feed screw. 57 is a locking lever pivoted on the screw 58 and anchored to the block 52, for locking the carriage against the reaction of the spring 56, to be more fully described. 59 is the holder for the blade 60 and is mounted on the block 52.

25 With the carriage out of the control of the feed screw, it is manually moved toward the rolls far enough to place a knife blade at the entrance and between the open polishing rolls and also place the screw 61, carried by the plate 51, directly under the finger 62, carried by the vertical rod 36.

With the members thus placed, the treadle is depressed to bring the finger 62 forcibly against the screw 61 and tilt the carriage to bring the nut 54 into engagement with the feed screw 41, Figure 4. This inward movement of the nut and plate 53 will permit the gravity lever 57 to lie in front of the plate 53, with its further movement limited by the pin 63, and thus maintain contact of nut and feed screw during the polishing operation. Depressing the treadle will also force down the bar 26 and boxes 5, 6 and 7, to bring the upper roll against the blade. Owing to the 45 connection of the short shaft 12 with the sleeve 10, said shaft will be carried down a trifle further and tilt the upper roll to conform to the taper face of the blade. This treadle action will also permit the spring 64, Figure 1, to swing the pivoted lever 65 onto the treadle and lock it in its lower position. As the bar 66 connects the lever 65 with the trip lever 67, the action of lever 65 will also set said trip lever in the position shown during the 55 travel of the carriage.

As the blades are subjected to an excessive gripping pressure during their lengthwise travel through the rolls, and their gradual withdrawal therefrom, it is very important 60 that the point of contact of the rolls with the blades be continuously changed to prevent overheating the rolls and blades, as this will soon shorten the life of the former, and also draw the temper of the latter. To avoid this 65 condition the feed screw 41 is preferably off-

set at an acute angle with respect to the bed 1 so that the outward travel of the knife holding carriage on the feed screw will progressively change the gripping point of contact between the rolls and blade.

When the blade has passed through the rolls, the trip 68, Figure 2, will strike the trip lever 67 and unlock the treadle lever 37 when the stored up tension in the springs 69, 70, and the springs under the bar 26, will return the trip lever to its normal position, and the bar control springs will carry said bar up against the nuts 71, Figure 1. As the studs 30, 31, and 32, are anchored respectively to the boxes 5, 6, and 7, said boxes and the upper polishing roll will be carried up with the bar 26 a distance sufficient to freely admit the entrance of a knife blade between the rolls.

Simultaneously with the release of the 85 treadle lever 37, the gravity lever 57, Figure 1, will contact with the rod 72 and release the carriage and halt its further travel.

The essential feature of the present invention is to pass the blade through opposed abrasion members in different lines of travel and continue the separate movements until the imperfections of the previous operations are effectually broken up and entirely obliterated. Rolls, instead of wheels, are the 95 indispensable elements in producing the desired results, for they permit the blade to remain in contact with the rolls long enough to fully complete the polishing operation. The rolls can be made of any desired length, 100 and, the tripping mechanism and the speed of the feed screw can be so timed that the blade can be withdrawn from the rolls at any desired period of the carriage's travel, and thus shorten or lengthen the polishing 105 operation conformably with the work to be done.

Having thus described my invention what I claim is:

1. In a machine of the character described, in combination, a bed, opposed cylindrical abrasive rolls mounted therein, a knife blade holding carriage, a support for the carriage, a rotatable feed screw journaled on the support, means for temporarily connecting the feed screw with the carriage, automatic tripping means for breaking the contact between the carriage and feed screw and halting the carriage, said feed screw offset at an acute angle with respect to the machine bed 110 so that the outward travel of the blade holding carriage will progressively change the gripping point of contact of the rolls with the blade during its passage between the rolls.

2. In a knife blade abrading machine, in 115 combination, a bed, standards mounted thereon, opposed cylindrical abrasion rolls mounted in the standards, a jack shaft flexibly connected with one end of the upper roll to slightly tilt the upper roll to taper the 120

faces of the blade when both rolls engage the blade, said upper roll and jack shaft journaled in spring supported boxes, a knife holding carriage, a support therefor, a rotatable feed screw journaled on the carriage and offset at an acute angle with respect to the bed, treadle mechanism for bringing the upper roll into operative engagement with the lower roll, and the knife holder into operative engagement with the feed screw.

10 In testimony whereof I affix my signature.
JOHN FUSCO.
